UNITED STATES PATENT OFFICE.

ELLA L. ROBERTS, OF LOS ANGELES, CALIFORNIA.

LADY'S UNDERGARMENT.

Application filed July 2, 1921. Serial No. 482,218.

To all whom it may concern:

Be it known that I, ELLA L. ROBERTS, a citizen of the United States, and a resident of Los Angeles, in the county of Los Angeles and State of California, have invented new and useful Improvements in Ladies' Undergarments, of which the following is a specification.

This invention relates to ladies' undergarments, and particularly to a form of undergarment which when worn will dispense with the usual petticoat and may be readily adapted to the form without discomfort and inconvenience.

The principal object of my invention is to provide an undergarment partaking somewhat of the characteristics of the type known as the "Teddybear." The garment may be made of any suitable material and is adapted to extend from a point below the arm-pits to the knees of the body, and is supported on the shoulders by means of narrow shoulder straps.

It will be understood that in garments of this character, now in vogue, the bottom of the garment is connected between the legs by means of relatively narrow extensions forming a part of the front and back, and adapted to be buttoned, clasped, or otherwise attached together, and usually a seam is provided which extends vertically in the center of the back of the garment, which, aside from being inconvenient and uncomfortable to the wearer, is visible through the outer clothes and is therefore more or less unsightly.

It is an object therefore, of my invention to provide a garment of the character mentioned in which the vertical seam in the back is omitted and the front and back of the garment are joined together at the sides, whereby seams will be invisible, and to provide the lower portion of the back, which extends around the trunk of the body in the form of a separate piece of material, attached at its upper edge by a seam to the upper portion of the back, and at its sides to the front portion. This seam, which serves to connect the two portions of the back of the garment, extends horizontally on the back of the garment at a point about at the waist-line, and is so arranged that a pair of box pleats are provided in the center of the back and extend from the waist-line downwardly, where-

by ample fullness may be provided around the hips and the larger portion of the body, when such fullness is necessary.

This feature of the garment, however, preserves a straight line effect when the wearer is in erect position, and the skirt portion of the garment assumes a natural droop.

It will be understood in this connection, that other forms of garments of this character are at times uncomfortable and inconvenient when the wearer is bending over or in sitting posture, for the reason that there is not enough fullness in the lower portion of the garment, and the material draws taut, and in time the fabric of which the material is made may wear and tear, due to the excessive strain imposed thereon.

It is another object of my invention to connect the lower portion of the back and front of the garment by means of a continuous strap, or extensions, or the front portion and lower portion of the back may be integrally formed from a single pattern, so as to provide a continuous strip extending between the legs for the purpose of holding the garment in proper position on the wearer and preventing the upward creeping thereof on the body.

With these and other objects in view, I will now describe my invention in detail by reference to the annexed drawings, which show one practical embodiment thereof and a preferred form of garment.

In the said drawings:

Fig. 1 is a back view of the garment in position on a person for use.

Fig. 2 is a side view of the same.

Fig. 3 is a rear view of the garment; and Fig. 4 is a fragmentary section of the bottom portion thereof.

By reference to the drawings it will be seen that the garment embodies a front F, made out of a single piece of material, and a back comprising an upper portion B and a lower portion B'. The front F and the back portion B are joined together by means of seams 1, 1 at the sides of the garment, and the back portion B is connected at its lower edge to the upper edge of the back portion B' by a seam 2, extending across the waist-line. The portion B' is also connected at the sides with the edges of the front portion F by means of seams

3, 3 which align with the seams 1, 1 connecting the upper portion of the back with said front portion. The upper end of the garment is formed into a horizontal encircling seam 4 to which shoulder straps S, S are suitably attached and are adapted to extend over the shoulders of the wearer for supporting the garment on the body.

Said straps are so positioned at the top 10 of the garment inwardly of the sides, as to provide ample space outside of the straps through which the arms may extend, and the top of the garment is adapted to be positioned sufficiently below the arm-pits as 15 to prevent discomfort and inconvenience to the wearer. The front portion F and the lower back portion B' are joined together in the center and at the bottom by means of an extension E which is adapted to be positioned between the legs, so as to prevent 20 the upward movement of the garment on the body. This extension is continuous and the front F is in effect a continuation of the back portion B', and is cut so that these 25 portions may be integrally formed, as shown, or they may be made of separate pieces of material, if desirable, and suitably stitched together at the bottom. The structure shown however, is preferable for 30 the reason that any seams at the point between the legs will be omitted and discomfort to the wearer will be obviated.

The back portion B' has a pair of box 35 plaits P, P which extend downwardly from the seam 2 at the waist-line to the bottom of the garment, so that when the wearer occupies a sitting posture or bends over, ample fullness will be provided in the bottom of the garment to accommodate the 40 garment to the position of the wearer without discomfort and inconvenience, and also without the attendant liability of tearing the material.

When the wearer of the garment stands 45 erect, it will be seen that the plaits P, P will draw the sides of the garment inwardly and the surplus material will be taken up thereby, so that no discomforting or inconvenient folds will be formed at the sides 50 or in the back, but when the body is bent over or in sitting position, these plaits afford ample fullness so as to permit the easy yielding of the garment outwardly toward the sides, for the purpose stated.

55 The legs of the body project through openings formed between the extension E and the sides of the garment, and in order to eliminate surplus material I cut the front and back portions F and B' on a bias as

at 5, 5, and provide pieces of material 6, 6 etc., for attachment to the front and back portions at such points, so that the garment will taper downwardly and inwardly from the hips and droop comfortably and loosely over the thighs.

65

It will be quite obvious that my garment is susceptible to modification within the scope of the appended claim without departing from the spirit of my invention, and the same is also susceptible to ornamentation on the front, back, sides and bottom, as may be deemed advisable and expedient, and to satisfy all classes of the trade.

70

It will be seen by reference to the drawings, that all of the seams of the garment 75 are arranged at such points that they may not be visible through the outer garments, and insure perfect comfort to the wearer, which would not be provided if the seams were extended vertically in the center of 80 the back and front, as in other garments now in vogue.

85

Other necessary and desirable features will readily be understood by those familiar with the manufacture and use of such garments, and it will also be obvious that the garments may be made of any suitable material with equal success and with like durability and comfort.

90

What I claim is:

A lady's undergarment comprising a front portion having its lower edge inclined downwardly from the sides, a continuing strip in the center thereof, diagonal portions attached to said lower edge on opposite sides 95 of the center, an upper back portion attached to said front portion at the sides and terminating in a substantially horizontal line at the waist, a central back portion attached to the lower edge of the upper back portion and having its lower edge inclined downwardly to the center and continuing in said central strip attached to said front portion, diagonal portions attached on opposite sides to the lower edge of said central back portion and attached to the diagonal portions on the front of the sides, leg openings being provided in said diagonal portions on opposite sides of said central strip, and a plait formed in said central back portion intermediate the sides, closed at the top and open at the bottom to provide fullness between the leg portions.
